UNITED STATES PATENT OFFICE.

FREDERIC V. HETZEL, OF PHILADELPHIA, PENNSYLVANIA, ASSIGNOR TO THE LINK BELT ENGINEERING COMPANY, OF PHILADELPHIA, PENNSYLVANIA, A CORPORATION OF PENNSYLVANIA.

BOX-ELEVATOR.

SPECIFICATION forming part of Letters Patent No. 716,037, dated December 16, 1902.

Application filed September 7, 1901. Serial No. 74,624. (No model.)

To all whom it may concern:

Be it known that I, FREDERIC V. HETZEL, a citizen of the United States, residing in Philadelphia, Pennsylvania, have invented certain 5 Improvements in Box-Elevators, of which the following is a specification.

The object of my invention is to prevent the swinging of the carrier of a box or package elevator when the carrier passes over the 10 head-wheel of the elevator mechanism.

In the accompanying drawings, Figure 1 is a front view of the upper portion of a box-elevator, illustrating my invention. Fig. 2 is a vertical sectional view on the line 2 2, 15 Fig. 1; and Figs. 3 and 4 are views of modifications of my invention.

My invention relates to that class of box or package elevators using one or two endless chains, from which are suspended at intervals the carrying platforms or studs for receiving the box or package to be elevated. In the drawings I have shown an elevator of the two-chain type. The chains pass around wheels at the bottom of the elevator structure 25 and wheels at the top, and in order to automatically discharge the box from the elevator the same is carried up to the full height of the elevator and discharged on the down-run, so as to enable the discharge-fingers to rest 30 under the box and remove it from the carrying-platform to the discharge-chute. In this type of elevator the carrying-platform tends to swing when carried over the head-wheel, and if the elevator is run at too high a speed 35 the box is liable to slide from the platform as it swings, and consequently the speed of the elevator has to be slow in order to prevent accidents. By my invention I prevent the swinging of the platforms as they pass over 40 the head-wheel, so that the speed of the elevator can be materially increased.

A A are two head-wheels having sprocket-teeth and secured to shafts A' A', which are mounted in bearings a a on the framework B 45 of the elevator structure. The space between the head-wheels A A is open, so as to allow the elevator-platforms to freely pass from the upper run to the lower. On the shafts A' A' are gear-wheels a', which mesh with pinions

c c on a shaft C, mounted in bearings c' on 50 the framework B. On the shaft C is a gear-wheel c², which meshes with a pinion c³ on a driving-shaft C', provided with a belt-pulley C², which is belted to any suitable power-shaft. By this arrangement the two sprocket-wheels 55 A A are driven at the same speed.

D D are the two endless chains of the elevator, which pass over the sprocket-head wheels A A, as shown, and around a suitable tail-wheel at the base of the elevator. 60

Carried by the chains D D in the present instance are carrying-platforms E, consisting of two arms e e, hung from two pivot-pins d d on the chains D D, which arms are connected together at their lower ends by a bar e'. Secured to the arms are two angle-plates e², which are of sufficient length to form a support for the box to be carried. Below the head-wheels is a shaft F, driven from one of the shafts A' A' through a train of gears f f' f², 70 and on this shaft are two disks F', which are so proportioned as to form a support or guide for the lower end of each platform as it passes around the head of the elevator. The portions e³ of each platform rest against the periphery of the disks F' during the time the platform passes from one side of the elevator to the other, thus preventing the platform from swinging, and yet allowing it freedom to accommodate itself, so that it will always 75 hang plumb. Discharge-fingers i i' are so arranged on the down-run of the elevator that while the platform will be free to pass the discharge-fingers the box will be engaged by the said fingers and transferred to a suitable 80 chute. Other means of discharging the elevator may be used without departing from my invention, and the means for driving the elevator may also be modified.

It will be understood that while I have 90 shown my invention especially designed for elevating boxes the platform may be arranged to carry bags or other packages in place of boxes, and instead of the elevator having two chains with the platforms between them a single chain D' may be used, as in Fig. 4, with an overhanging carrier E' in the form of a platform or stud. The rotating 95

disks may be driven by a chain from one of the head-shafts instead of by the train of gears shown, if desired.

Fig. 3 is a modification in which in place 5 of a disk having a plain periphery I have shown a sprocket-wheel the spaces between the teeth of which are so shaped as to receive a projection on the under side of each platform.

10 I claim as my invention—

15 1. The combination in an elevator for boxes and like objects, of an endless-belt elevator, carriers hung from said elevator, head-wheels around which the elevator passes, and a rotating guide against which the base of each carrier rests in passing from one side of the elevator to the other, whereby the swinging of the carrier is prevented without tipping the carrier, substantially as described.

20 2. The combination in an elevator for boxes and like objects, of head-wheels, means for driving the same, endless chains passing around the head-wheels, platforms suspended from said chains, a driven disk mounted so that the lower portion of each platform will bear against the disk in passing from one side of the elevator to the other, substantially as described.

25 3. The combination in an elevator for boxes and like objects, of two head-wheels, means

for driving said head-wheels, an elevator consisting of two endless chains arranged to pass around said head-wheels, platforms suspended from said chains, at intervals, a driven shaft mounted below the head-wheels, disks on said shaft, said disks being so arranged with respect to the head-wheels that the lower portion of each platform will rest against the disks in passing from one side of the elevator to the other, substantially as described. 35

40 4. The combination in a box-elevator, of two head-wheels, means for driving said head-wheels, two endless chains mounted on said head-wheels, a series of platforms, each platform consisting of two arms hung from the chains and connected by a cross-bar and having supports for the box, with a shaft mounted below the head-wheels, and having two disks so spaced that the lower portions of the arms will rest against them as the platforms pass 45 around the head-wheels from one side of the elevator to the other, substantially as described.

45 In testimony whereof I have signed my name to this specification in the presence of 50 two subscribing witnesses.

FREDERIC V. HETZEL.
